United States Patent Office

Des. 198,601
Patented July 7, 1964

198,601

CAMERA

Samuel E. Hohulin, Davenport, Iowa, assignor, by mesne assignments, to Chicago Aerial Industries, Inc., Barrington, Ill., a corporation of Delaware

Filed Sept. 27, 1963, Ser. No. 76,778

Term of patent 14 years

(Cl. D61—1)

Fig 1

Fig 2

FIGURE 1 is a front perspective view of a camera showing my new design; and

FIGURE 2 is a rear perspective view thereof.

The bottom of the camera, not shown, is plain and unornamented.

I claim:

The ornamental design for a camera, as shown and described.
